CLAIM

The ornamental design for a shell for a limousine for individuals in wheel chairs, as shown and described.

DESCRIPTION

FIG. 1 is a front-top perspective view of a shell for a limousine for individuals in wheelchairs, showing my new design;

FIG. 2 is an enlarged front-top perspective view of the shell;

FIG. 3 is a top view of the shell;

FIG. 4 is a right side view of the shell;

FIG. 5 is a left side view of the shell;

FIG. 6 is a front view of the shell; and,

FIG. 7 is a rear view of the shell.

The broken line showing of environment is for illustrative purposes only and forms no part of the claimed design.
